UNITED STATES PATENT OFFICE.

BENJAMIN F. WOOD, JR., OF CAMDEN POINT, MISSOURI, ASSIGNOR OF ONE-HALF TO DAVID C. LEAVEL, OF SAME PLACE.

STOVEPIPE-JOINT LOCK.

SPECIFICATION forming part of Letters Patent No. 635,707, dated October 24, 1899.

Application filed March 6, 1899. Serial No. 708,012. (No model.)

To all whom it may concern:

Be it known that I, BENJAMIN F. WOOD, Jr., a citizen of the United States, residing at Camden Point, in the county of Platte and 5 State of Missouri, have invented certain new and useful Improvements in Stovepipe-Joint Locks, of which the following is a specification, reference being had therein to the accompanying drawings.

10 This invention relates to locking mechanism for stovepipe-joints.

The object of the invention is to produce a mechanism by which a stovepipe-joint may be firmly held in position to communicate 15 with a chimney-flue and prevented from either entering too deeply into the chimney or escaping therefrom or from in any wise sagging or swaying, and by which the joints may be held firmly.

20 Figure 1 is a side elevation of a pipe-joint and elbow, showing section of chimney and pipe-lock in position. Fig. 2 is a broken bottom plan of a pipe-joint, showing the chimney hook and braces and draw-coupling for 25 wire, the pipe being partly broken away to show inside plate and lugs and one brace being in section. Fig. 3 is a plan, and Fig. 4 an elevation, of the retaining-hook and its hinged extension, Fig. 4 showing the wire-clamping mechanism in section.

A indicates the pipe-section which enters the chimney, and B the chimney, both being of any common construction.

C indicates a hook, preferably of wire and 35 hinged to a metallic strap D, which strap D is provided with a number of holes. The strap D is attached to the stovepipe-joint by a bolt E, having a retaining-nut E' thereon and passing through one of the holes in the strap 40 and a hole in the stovepipe. The end of the hook C should project from the end of the stovepipe far enough to drop down inside the chimney-flue when the pipe is adjusted in the flue. The holes in the strap D enable the

45 connection to be made with proper adjustment of hook whether the wall of the chimney-flue be thick or thin. Except for the extension of strap D and the provision of a number of holes therein, this mechanism is old. The 50 hook C is slightly lifted when the joint is en-

tered into the flue opening or thimble and slides along on the lower part of the thimble until it drops inside the flue to lock the pipe against withdrawal. When it is desired to withdraw the pipe, it is rotated in the hole 55 until the hook is at the upper side, when it will drop free.

At each side of the joint A, I attach a brace F. Said brace is slotted lengthwise, as indicated, and has a right-angled arm or extension F'.

Inside the pipe I place a metallic strip G at each side of the pipe and secured by rivets H H, which rivets have heads or lugs projecting outside the stovepipe. A threaded 60 bolt I passes through the strap and pipe, and a nut K outside the pipe serves to attach brace F.

The braces F are applied at each side of the pipe-joint, the rivets H extending into the 65 slot in the brace and holding it in longitudinal relation to the pipe and the nut K serving to retain the brace F in endwise adjustment, so that extension F' of each of said braces will come against the outer wall of the 70 chimney at the sides of the pipe when the hook engages the inside of the flue.

Flue-locks something like mine have been heretofore made in which a single brace like F was applied to the under side of the pipe-joint, 80 directly under hook C. This is objectionable in that it will permit the outer end of the joint to sag or to swing sidewise. Such is not the case with my attachment, wherein the hook C at bottom and the two braces F at the sides 85 of the pipe mutually brace and support each other. When the joint is properly adjusted in the chimney and the two braces applied, as indicated by Figs. 1 and 2, the joint is held rigidly in the thimble or flue opening, so that it 90 will not only support itself, but will support other joints of pipe with extreme rigidity.

Many accidents have happened from an inefficient fastening of stovepipes in chimneys.

With the mechanism described no displacement of the pipe can take place until the locking mechanism is displaced by proper means unless some part be broken.

As a means for locking the remaining joints of pipe to the joint A a bent strap M is pro- 100

vided. This strap M may be generally similar to one of the braces F, but it is not necessary that it shall be slotted, as a hole for the passage of the bolt E is sufficient. The arm 5 M' of strap M is also perforated for the passage of the draw-bolt O, which bolt is provided with a nut P and is of usual construction. A wire R may be attached to this draw-bolt and so extend around the elbow A². Of course the same connection may be made no matter how many joints of pipe intervene between pipe A and elbow A². Whether the wire R pass around an elbow or is otherwise connected to the pipe-sections the wire may 10 be drawn taut by turning the nut P, thus binding all of the pipe connected to the wire to the bolt E, and so to the hook C in the chimney, and as the pipe-section A is rigidly held and braced in the chimney so will all the 15 pipe-sections be held as far as wire R extends.

I am aware that most if not all the elements of my locking mechanism have been used in somewhat similar relation for a like 20 purpose; but I am not aware that any prior inventor has combined and arranged these elements so as to produce an effective and reliable locking-coupling for pipes and chimneys in the way I have described.

What I claim is—

1. The combination with a stovepipe-joint, 30 of a metallic strap inside the pipe, rivets and a screw-bolt passing through said strap and projecting outside thereof, and a slotted brace, into the slot of which said rivets extend to 35 guide the same, the bolt and its nut forming means for adjustably securing the brace, substantially as described.

2. In a stovepipe-locking device as described, the combination with the chimney 40 and pipe of a hinged hook extending into the chimney at the lower side of the pipe, a bolt passing through the hook-support and through the pipe, a bent strap secured to said bolt outside the pipe, a draw-bolt passing through an arm of the bent strap and having a wire connected thereto for binding outer sections or joints of pipes, and side 45 braces on the chimney-joint, whereby all the sections reached by the wire are bound to the 50 chimney and braced therefrom, substantially as described.

In testimony whereof I affix my signature in presence of two witnesses.

BENJAMIN F. WOOD, JR.
